UNITED STATES PATENT OFFICE

2,365,981

PRODUCTION OF CHLORINATED NITRO HYDROCARBONS

John B. Tindall, Terre Haute, Ind., assignor to
Commercial Solvents Corporation, Terre Haute,
Ind., a corporation of Maryland

No Drawing. Application December 20, 1941,
Serial No. 423,765

8 Claims. (Cl. 260—644)

The present invention relates to a process for the preparation of chlorinated nitro hydrocarbons, and more particularly it is concerned with a process whereby the hydrogen atoms attached to the carbon atom holding the nitro group of the nitro hydrocarbon may be completely replaced by chlorine. A particular class of chlorinated nitro hydrocarbons which can be produced in accordance with the present invention is the group of chloronitroalkanes of the type:

in which the substituents R and R' may represent either chlorine or an alkyl group.

A sub-class of nitroalkanes falling within the group represented by the above generic formula is the group of nitroalkanes of the formula:

in which R is an alkyl group. Chloronitroalkanes included by the above formula are 1,1-dichloro-1-nitroethane, 1,1 - dichloro - 1-nitropropane, 1,1-dichloro-1-nitrobutane, 1,1-dichloro-1-nitroisobutane, 1,1 - dichloro - 1 - nitropentane and the like.

While my invention is especially adapted to the preparation of the 1,1-dichloro-1-nitroalkanes, it is to be understood that it is not restricted thereto, but also includes such chlorinated nitro hydrocarbons as 2-chloro-2-nitropropane, and 2-chloro-2-nitrobutane, as well as other chlorinated nitro alkanes in which the nitro group is attached to either a primary or secondary carbon atom, and the term "chlorinated nitro alkanes" appearing in certain of the accompanying claims is to be so interpreted.

I am aware of the fact that chlorinated nitro alkanes, included in the class contemplated by the present invention, have previously been prepared. However, the conditions provided by the methods formerly employed do not favor the procurement of commercially practical yields. For example, 1,1-dichloro-1-nitro-alkanes have previously been prepared by first producing the 1-chloro-1-nitroalkane in accordance with any of several known methods, after which the resulting 1-chloro-1-nitroalkane was introduced into an alkaline solution, such as for example, an aqueous solution of an alkali or alkaline earth metal hydroxide, preferably containing the metal

hydroxide in the amount theoretically required to produce the corresponding salt of the 1-chloro-1-nitroalkane. Chlorine was then introduced into the resulting solution in an amount theoretically required to convert the 1-chloro-1-aci-nitroalkane salt into the corresponding 1,1-dichloro-1-nitroalkane. In carrying out this reaction under such conditions, an appreciable quantity of the 1-chloro-1-aci-nitroalkane salt is present in an alkaline medium for a substantial period of time. Otherwise stated, a certain amount of the salt is present in the alkaline medium until a quantity of chlorine has been introduced which is sufficient to convert all of the 15 salt into the corresponding 1,1-dichloro-1-nitroalkane. Such reaction conditions are definitely unfavorable with respect to the formation of the desired 1,1-dichloro-1-nitroalkanes since I have found that the metal salts of the 1-chloro-1-aci-nitroalkanes are relatively unstable under these 20 circumstances, and this finding has been confirmed by the comparatively low yields obtainable by the procedure mentioned immediately above. In addition to the fact that such a process gives commercially impractical yields, there 25 is also the further disadvantage that it involves two separate and distinct steps which necessarily entail added operation costs.

Other prior procedures for the chlorination 30 of nitro alkanes have employed a metal hypochlorite as a chlorinating agent, in which the hypochlorite is produced from a suitable base, such as sodium hydroxide, in the presence of relatively large volumes of the nitro alkane. Under such circumstances, a competing reaction 35 for the nitro alkane exists between the metal hydroxide and metal hypochlorite. Obviously, therefore, the yield of the desired chloro nitro alkane is materially decreased. In addition, the 40 reaction of the metal hydroxide with the nitro alkane frequently leads to the formation of various complex products, the character of which is not entirely known. As a result of the presence of such products in the reaction mixture, 45 purification of the chlorinated nitro alkane thus produced becomes considerably more difficult.

I have now discovered that chlorinated nitro alkanes may be conveniently prepared from the corresponding nitro alkane by means of a procedure free from the above mentioned disadvantages. A preferred embodiment of the present invention consists of first preparing an aqueous alkaline solution of a suitable metal hypochlorite by adding to a relatively strong alkaline solution 55 sufficient chlorine to bring the pH thereof to a

value of between 10 and 14. To this resulting solution is then added, with thorough agitation, the desired nitro alkane, the quantity of the latter added being such that a slight excess of hypochlorite is present in the reaction mixture at all times. After the entire quantity of nitro alkane has thus been added, the crude reaction mixture may then be subjected to steam distillation and the chlorinated nitro alkane recovered in substantially pure form. In this connection the expression "slight excess," as used in the present description and claims, is to be construed as representing a quantity of hypochlorite lying intermediate the amount theoretically required to replace, with chlorine, the reactive hydrogen atom or atoms attached to the carbon holding the nitro group, and approximately a 20 per cent excess of said theoretical amount.

A modification of the above general procedure comprises producing an alkaline hypochlorite solution by adding sufficient chlorine to a strong alkaline solution to bring the pH thereof to a value of between about 13 and 14. A deficiency of nitro alkane, with respect to the hypochlorite present, is then added together with sufficient chlorine to reconvert the alkali, produced by the action of hypochlorite on the nitro alkane, to hypochlorite, which is in turn used for chlorinating additional nitro alkane. In carrying out my invention in accordance with this procedure, an excess of hypochlorite over nitro alkane is always maintained, and although the medium remains alkaline throughout the course of the reaction, the presence of excess hypochlorite avoids the above mentioned undesirable side reactions which are obtained when the metal hypochlorite is formed in the presence of an excess of nitro alkane.

Although in the procedure last described, a pH of between 13 and 14 is specified, it may be said, in general, that any means by which the pH of the medium can be maintained at a value of between 10 and 14 throughout the course of the reaction will result in satisfactory yields of chlorinated nitro alkanes. The necessity of maintaining the reaction medium within the aforesaid pH range results from the fact that relatively concentrated solutions of hypochlorites, in general, are unstable in the absence of alkali. The concentration of hypochlorite in solution, however, should not be permitted to appreciably exceed 20 per cent even though such solutions are stabilized by the presence of alkali, for the reason that hypochlorites, when in concentrations appreciably exceeding this value, tend to be readily transformed into the corresponding chlorates. The presence of chlorates in the chlorinating medium, in addition to retarding the velocity of the action of hypochlorites on the nitro alkane to give the corresponding chlorinated nitro derivative, promotes the occurrence of objectionable oxidation reactions, causing a substantial decrease in the yield of chlorinated nitro alkanes as well as also rendering the purification thereof much more difficult.

In carrying out the present invention, it is essential that sufficient water be present in the medium to facilitate the reaction between the alkali and chlorine to form the hypochlorite, which in turn reacts with the nitro alkane. Likewise, it is desirable to maintain water in the reaction medium in amounts sufficient to dissolve the metal chloride formed as a by-product of the reaction.

The temperature at which my process can be carried out will vary with the nature of the nitro

alkane employed, i. e., in general, the higher the carbon content of the nitro alkane, the higher the necessary reaction temperature. In the majority of instances, however, I have found that my process is most effectively carried out at temperatures ranging from about 20° to not in substantial excess of 100° C., if adequate agitation and means of cooling are provided throughout chlorination.

In general, it may be said that any nitro alkane in which the nitro group is attached to either a primary or secondary aliphatic carbon atom can be chlorinated in accordance with the process of the present invention. A specific class of nitro alkanes coming within the above definition is the family of nitroalkanes of the formula:

in which R and R' may represent either hydrogen or alkyl. Examples of such nitroalkanes are nitromethane, nitroethane, 1-nitropropane, 2-nitropropane, 1-nitrobutane, 2-nitrobutane, 1-nitropentane, 2-nitropentane and the like. Additional nitro alkanes which may be chlorinated in accordance with my invention are other nitro alkanes in which the nitro group is attached to either a primary or secondary carbon atom.

The examples which follow, although typical of the high yields that are obtainable as a result of the present invention, are in no way to be considered as limiting the scope thereof.

Example I

Into a solution consisting of 600 parts of water and 58 parts of sodium hydroxide was introduced approximately 51 parts of chlorine. The pH value of the resulting mixture was between 12.5 and 13. Eleven and two-tenths parts of nitromethane was then slowly added with agitation at a temperature of between 20 and 25° C. After all of the nitromethane had been introduced, agitation was continued until chlorination appeared to be substantially complete as evidenced by a decrease in the temperature of the reaction mixture. The crude chlorinated product, trichloronitromethane, was then steam distilled, this operation being continued until the distillate came over clear. The quantity of trichloronitromethane obtained in this manner amounted to a yield of 96 per cent.

Example II

Eighty parts of sodium hydroxide in the form of a 3.7 normal aqueous solution was placed into a suitable reaction flask after which approximately 49 parts of chlorine was introduced. At this point nitromethane was added simultaneously with the chlorine in a ratio of three moles of chlorine to one of nitromethane. This procedure was continued until 122.7 parts of chlorine and 31 parts of nitromethane had been added. The pH of the mixture during the course of the reaction remained between 10 and 14. After the chlorine and nitromethane were introduced in the manner described above, the reaction mixture was steam distilled and trichloronitromethane obtained in 92.2 per cent yield.

Example III

Fifty parts of chlorine was introduced into 600 parts of water containing 64 parts of sodium hydroxide. To this resulting alkaline solution was added with thorough agitation at a tem-

perature of 25° C., 20.8 parts of nitroethane. The 1,1-dichloro-1-nitroethane thus produced was isolated in the manner set forth in Example I and obtained in 99.6 per cent yield. The pH of the reaction mixture throughout the chlorination was between 11.5 and 14.

Example IV

An alkaline solution of hypochlorite was prepared by introducing 162.6 parts of chlorine into 1590 parts of water containing 210 parts of sodium hydroxide, at a temperature of between 20 and 25° C. The resulting mixture was then cooled to a temperature of 18° C. after which 68.2 parts of nitroethane was slowly added with thorough agitation. During the course of the introduction of nitroethane, the temperature of the reaction mixture rose to approximately 40° C. At the conclusion of the addition of nitroethane, the crude product was steam distilled and the 1,1-dichloro-1-nitroethane obtained in a yield of 100 per cent. The pH of the mixture during the reaction was between 11.5 and 14.

Example V

1,1-dichloro-1-nitropropane was prepared by slowly introducing at a temperature of 30° C., 24.5 parts of 1-nitropropane into a solution containing 600 parts of water, 64 parts of sodium hydroxide and 50 parts of chlorine. On steam distillation of the resulting reaction mixture, 1,1-dichloro-1-nitropropane, representing a 99.2 per cent yield, was recovered. The pH of the reaction mixture throughout the chlorination remained between 11.5 and 14.

Example VI

2-chloro-2-nitropropane was prepared by slowly adding 49.9 parts of 2-nitropropane to an alkaline sodium hypochlorite solution, prepared by introducing 50 parts of chlorine into a solution consisting of 600 parts of water and 64 parts of sodium hydroxide. The addition of nitropropane was carried out at 25° C. during which time the reaction mixture was thoroughly agitated. At the conclusion of the addition of 2-nitropropane, the crude product was worked up in the usual manner to give 2-chloro-2-nitropropane in a yield of 96.4 per cent. The pH of the reaction mixture was between 11.5 and 14.

Example VII

To a sodium hypochlorite solution, prepared by the addition of 50 parts of chlorine to a solution consisting of 600 parts of water and 64 parts of sodium hydroxide, was added with vigorous agitation, at a temperature of 30° C., 53.5 parts of 2-nitrobutane. During the addition of 2-nitrobutane, considerable heat of reaction was evolved; however, the temperature of the reaction mixture was maintained between 45 and 50° C. by means of external cooling when necessary. After all of the 2-nitrobutane had been added, the mixture was agitated until the temperature fell to about 25° C. This mixture was then steam distilled and 2-chloro-2-nitrobutane was recovered in a yield of 98.3 per cent. The pH of the mixture throughout the reaction was between 11.5 and 14.

While I have only mentioned, in the above examples, the use of sodium hydroxide as the base which may be employed in the preparation of the metal hypochlorite, I do not desire to be limited thereto since the water soluble alkali and alkaline earth metal hydroxides and carbonates,

in general, are equally suitable for this purpose.

Also, it is to be understood that the scope of the present invention is not limited to the specific procedures outlined by the above examples, but on the contrary, includes numerous modifications thereof. For example, the nitro hydrocarbon, chlorine, and base may all three be added concurrently to the necessary amount of water, the only requirements being, in case such a procedure is used, that sufficient alkali be present to maintain the pH of the reaction mixture between the value of 10 and 14 and that the quantity of chlorine added, and present in solution as hypochlorite, is always in slight excess over the nitro hydrocarbon employed. Other such modifications which involve the principles of the present invention will be evident to those skilled in the art. Therefore, it is to be understood that my invention covers all methods which are concerned with the production of chlorinated nitro hydrocarbons of the type specified by chlorinating the corresponding nitro hydrocarbon with a metal hypochlorite at a pH of between 10 and 14 wherein the chlorine, present in the mixture as hypochlorite, always remains in excess over the quantity of nitro hydrocarbon added.

Having described my invention, what I claim is:

1. A process for the liquid phase production of chlorinated nitro alkanes which comprises adding to a solution of a metal hydroxide selected from the group consisting of alkali and alkaline-earth metal hydroxides, sufficient chlorine to bring the pH of said solution to a value of between 10 and 14, and to produce the corresponding metal hypochlorite, adding to the resultant metal hypochlorite a nitroalkane in which the nito group is bound to a carbon atom having from one to three hydrogen atoms, said nitroalkane being added to said hypochlorite solution so that a slight excess of said hypochlorite is present in the reaction mixture at all times.

2. A process for the liquid phase production of chlorinated nitroalkanes of the formula:

wherein R and R' each represent an alkyl group, which comprises adding to a solution of a metal hydroxide selected from the group consisting of alkali and alkaline-earth metal hydroxides, sufficient chlorine to bring the pH of said solution to a value of between 10 and 14, and to produce the corresponding metal hypochlorite, adding to the resultant metal hypochlorite solution a nitroalkane of the formula

wherein R and R' represent alkyl groups, said nitroalkane being added to said hypochlorite solution so that a slight excess of said hypochlorite is present in the reaction mixture at all times.

3. A process for the liquid phase production of chlorinated nitroalkanes of the formula:

wherein R represents an alkyl group, which comprises adding to a solution of a metal hydroxide selected from the group consisting of alkali and

alkaline earth metal hydroxides, sufficient chlorine to bring the pH of said solution to a value of between 10 and 14 and to produce the corresponding metal hypochlorite, adding to the resultant metal hypochlorite solution a nitroalkane in which the nitro group is attached to a primary carbon atom, said nitroalkane being added to said hypochlorite solution so that a slight excess of said hypochlorite is present in the reaction mixture at all times.

4. A process for the production of 1,1-dichloro-1-nitroethane which comprises adding to a solution of a metal hydroxide selected from the group consisting of alkali and alkaline earth metal hydroxides, sufficient chlorine to bring the pH of said solution to a value of between 10 and 14 to produce the corresponding metal hypochlorite, adding to the resultant metal hypochlorite solution nitroethane, said nitroethane being added to said hypochlorite solution so that a slight excess of said hypochlorite is present in the reaction mixture at all times.

5. A process for the production of 2-chloro-2-nitropropane which comprises adding to a solution of a metal hydroxide selected from the group consisting of alkali and alkaline earth metal hydroxides, sufficient chlorine to bring the pH of said solution to a value of between 10 and 14 and to produce the corresponding metal hypochlorite, adding to the resultant metal hypochlorite solution 2-nitropropane, said 2-nitropropane being added to said hypochlorite solution so that a slight excess of said hypochlorite is present in the reaction mixture at all times.

6. A process for the production of 2-chloro-2-nitrobutane which comprises adding to a solution of a metal hydroxide selected from the group consisting of alkali and alkaline earth metal hydroxides, sufficient chlorine to bring the pH of said solution to a value of between 10 and 14 and to produce the corresponding metal hypochlorite, adding to the resultant metal hypochlorite solution 2-nitrobutane, said nitrobutane being added to said hypochlorite solution so that a slight ex-

cess of said hypochlorite is present in the reaction mixture at all times.

7. A process for the liquid phase production of chlorinated nitroalkanes of the formula:

10 wherein R represents an alkyl group of less than five carbon atoms, which comprises adding to a solution of a metal hydroxide selected from the group consisting of alkali and alkaline-earth metal hydroxides, sufficient chlorine to bring the pH of said solution to a value of between 10 and 14 to produce the corresponding metal hypochlorite, adding to the resultant metal hypochlorite solution a nitroalkane of the formula,

15 wherein R represents an alkyl group having less than five carbon atoms, said nitroalkane being added to said hypochlorite solution so that a slight excess of said hypochlorite is present in the reaction mixture at all times.

20 8. A process for the liquid phase production of chlorinated nitro alkanes, which comprises adding to a solution of a metal hydroxide selected from the group consisting of alkali and alkaline earth metal hydroxides, sufficient chlorine to bring the pH of said solution to a value of between 10 and 14 and to produce the corresponding metal hypochlorite, adding to the resultant metal hypochlorite solution, chlorine and a nitroalkane 25 in which the nitro group is bound to a carbon atom having from one to two hydrogen atoms, said chlorine and nitrohydrocarbon being added at such a rate and in such amounts that the pH remains between 10 and 14 at all times and an excess of hypochlorite is present in the reaction mixture at all times.

35 JOHN B. TINDALL.
